UNITED STATES PATENT OFFICE.

OSCAR M. DAMM AND HERMAN WOBBE, JR., OF ST. LOUIS, MISSOURI.

BRUSH-MAKING MACHINE.

1,279,282.

Specification of Letters Patent. Patented Sept. 17, 1918.

Application filed December 18, 1917. Serial No. 207,664.

To all whom it may concern:

Be it known that we, OSCAR M. DAMM and HERMAN WOBBE, Jr., citizens of the United States, residing at St. Louis, Missouri, have invented a certain new and useful Improvement in Brush-Making Machines, of which the following is a full, clear, and exact description, such as will enable others skilled in the art to which it appertains to make and use the same, reference being had to the accompanying drawings, forming part of this specification.

Our invention relates to brush making machinery and more particularly to a machine for making the type of rotary brush which is disclosed in our copending patent application filed Dec. 18, 1917, Serial Number 207,665, the principal object of our invention being to provide a comparatively simple and easily operated machine which can be used for effectively and economically placing the flexible members of a rotary brush upon the periphery of the substantially cylindrical brush body.

A further object of our invention is to provide a comparatively simple machine which will be effective in materially reducing the time and labor ordinarily involved in the production of rotary or circular brushes.

With the foregoing and other objects in view, our invention consists in certain novel features of construction and arrangement of parts, hereinafter more fully described and claimed, and illustrated in the accompanying drawings, in which—

Figure 1 is a elevational view of a brush making machine of our improved construction, parts thereof being broken away.

Fig. 2 is a perspective view of parts of our improved machine, said parts serving as a support for the bristles or flexible members of the brush.

Fig. 3 is an enlarged vertical section taken approximately on the line 3—3 of Fig. 1.

Fig. 4 is a plan view of the rear end of the bristle supporting frame of the machine.

Fig. 5 is a detail section of the bristle supporting frame with a layer of bristles or the like positioned thereupon.

Fig. 6 is a detail section similar to Fig. 5 and showing the bristles forced downwardly into the supporting frame.

Fig. 7 is a sectional view of the bristle

supporting frame with bristles positioned therein, and said frame in position to be placed in the machine.

Referring by numerals to the accompanying drawings which illustrate a practical embodiment of our improved machine, 10 designates a suitable table, the same being supported in any suitable manner in a horizontal position, and formed in the top of said table is a longitudinally disposed 60 groove 11. Positioned on the sides of the machine near the center thereof are uprights 12 and 13, the same being provided at their upper ends with bearings 14 and 15 respectively. Journaled in these bearings 65 is a shaft 16 provided on one end with a crank handle 17 and the other end of said shaft or that end which operates in bearing 14 is provided with a spirally disposed groove 18.

Removably positioned in an aperture formed in bearing 14 is a pin 19, the inner end of which is normally positioned in the groove 18. The shaft 16 is adapted to receive the head or body A of a rotary brush, 70 said body being preferably of the type disclosed in my above mentioned application.

Removably positioned on the table 10 and adapted to slide in the groove 11 thereon is the frame which supports the bristles or like flexible members which are secured to the brush body A, said frame including a pair of rails 20 and 21, the same being spaced a slight distance apart and occupying the same horizontal plane.

Secured to the inner edge of rail 20 and depending therefrom is a vertically disposed rail 22 and secured to the underside of rail 21 at the inner edge thereof is an angle bar 23, the vertical flange of which lies parallel with rail 22. The ends 23^a of this angle bar are bent at right angles to the body thereof and said bent ends are secured to the ends of rail 22. (See Fig. 4).

The rear end of rail 20 is extended a short 95 distance beyond the corresponding end of rail 21 and positioned on said extended end is a block 20^a above which is positioned a pivotally mounted eccentric disk 20^b, the same being provided with an operating handle 20^c.

Adapted to be positioned in the space between the rails 20 and 21 and rail 22 and the vertical leg of angle bar 23 is a rail 24, 105 preferably of metal, and formed in one of 110

the edges thereof is a groove 25. Fulcrumed on top of the table 10 to one side of the groove 11 therein is a lever 26 and journaled thereupon is a roller 27 which normally bears directly upon rail 20 when the bristle supporting frame is positioned on the table 10.

Secured to the end of the lever 26 opposite to the fulcrumed end is the upper end of a rod 28, the lower end of which is connected to a pedal or the like.

When our improved machine is used for applying bristles or the like to a substantially cylindrical brush body such as A, the bristle supporting frame comprising the rails 20 and 21 and associated parts is removed from the table 10 and turned upside down or with said rails 20 and 21 uppermost.

20 A layer of bristles, hair, fiber or the like is now positioned on top of rails 20 and 21, as illustrated in Fig. 2, after which a suitable adhesive such as rubber cement is now placed on the central portion of said layer of bristles. (See Fig. 5).

The grooved edge of rail 24 is now laid directly upon the central portion of the layer of fibers or the like, and as said rail is pressed downward, the fibers are bent double and forced downward through the space between rails 20 and 21, and between rail 22 and the vertical leg of angle 23. (See Fig. 6). This downward movement of the rail and bristles is continued until the edge of said rail and the central portions of the bristles project beyond the outer edges of rail 22 and vertical flange of angle 23, after which the frame is inverted and a suitable adhesive, such as rubber cement, is applied to the projecting portion of the row of bristles. (See Fig. 7).

40 A flexible member such as a wire B is now threaded through the groove 25 and the rear end of said flexible member is clamped between the eccentric disk 20^b and block 20^a. The bristle supporting frame is now positioned on table 10 with the rails 20 and 21 occupying the groove 11, and the forward end of flexible member B or the end opposite the end which is clamped to block 20^a is secured to brush body A at one end of the groove in the periphery thereof.

50 Shaft 16 is now rotated by proper manipulation of crank handle 17 and as this movement takes place, the shaft and head A mounted thereon are moved laterally owing to the engagement of the inner end of pin 19 in groove 18.

60 As rotary motion is thus imparted to brush body A, the wire over which the bristles are doubled will be wound into the groove on said body, and thus the doubled ends of said bristles will be seated in said groove where they will be securely held by 65 the retaining member or wire B and the

adhesive or cement, which latter, it will be understood, becomes hardened when dry.

Necessarily as the flexible member and bristles are wound onto the brush body, the bristle supporting frame will be moved forwardly through groove 11, and when the groove in said brush body has been entirely filled, the end of the flexible member B is released from parts 20^a and 20^b and said end is secured to body A in any suitable manner.

In the event that the bristle holding frame slides too freely through groove 11, the operator can move rod 28 downwardly, thereby causing roller 27 to engage with pressure on rail 20, and this will create friction to cause the frame to move more slowly, thereby insuring the seating of the retaining member B and doubled ends of the bristles in the groove in brush body A.

80 After the bristles or flexible member have been applied to body A, the shaft 16 is removed from its bearings and said body is removed from the shaft.

85 A machine of our improved construction is comparatively simple, can be easily operated, and is effective in saving much time, labor and consequent expense in the manufacture of rotary brushes.

90 It will be readily understood that minor changes in the size, form and construction of the various parts of our improved machine may be made and substituted for those herein shown and described, without departing from the spirit of our invention, the scope of which is set forth in the appended claims.

95 We claim:

1. In a brush making machine, a support, a shaft journaled for rotation above said support and adapted to carry the brush body, a member arranged for sliding movement on the support and adapted to support the bristle carrying flexible member which is applied to said brush body, and means at the rear end of said sliding member for securing one end of the flexible member.

105 2. In a brush making machine, a support, a shaft journaled for rotation above said support and adapted to carry the brush body, a member arranged for sliding movement on the support and adapted to support the bristle carrying flexible member which is applied to said brush body, and means for applying pressure to the slidable member to retard its movement on the support toward the shaft.

110 3. In a brush making machine, a support, a shaft journaled for rotation above said support and adapted to carry the brush body, means for moving the shaft lengthwise during its rotary movement, a member arranged for sliding movement on the support and adapted to support the bristle carrying flexible member which is applied to said

brush body, and means at the rear end of said sliding member for securing one end of said flexible member.

4. In a brush making machine of the class described, a pair of spaced supports for the flexible elements of a brush, and a rail adapted to be inserted between said spaced supports for bending the flexible elements double, said rail being provided in one of its edges with a groove adapted to receive a flexible member which retains the flexible elements on the brush body to which said member and elements are applied.

5. In a brush making machine, a support, a shaft mounted for rotary and lengthwise movement above said support and adapted to carry the brush body, a member arranged for sliding movement upon said support, which member comprises a pair of spaced supports, a grooved rail adapted to be positioned between said supports, and a clamp on the rear end of said sliding member.

6. In a brush making machine, a table, a shaft journaled above said table and adapted to receive the brush body, a frame arranged for sliding movement on the table for holding the flexible members which are applied to the brush body, said frame comprising a pair of spaced supports, a grooved rail adapted to be positioned between said supports, and a clamp on the rear end of said frame.

7. In a brush making machine, a table, a shaft journaled above said table and adapted to receive the brush body, a member arranged for sliding movement on the table for holding the flexible members which are applied to the brush body, said member comprising a pair of spaced supports, a grooved rail adapted to be positioned between the spaced supports, and a clamp on the rear end of said sliding member, and means for applying variable pressure to the slideable member during its movement on the table toward the shaft.

8. In a machine of the class described, a table, and a frame arranged for sliding movement on said table, which frame is provided with an elongated longitudinally disposed slot, which is adapted to receive flexible brush elements, a grooved rail adapted to be positioned in said slot to grip the brush elements therein, the groove in said rail being adapted to receive a flexible member which retains the flexible elements on the brush body to which they are applied, and means on the rear end of said sliding frame for gripping the end of said flexible member.

In testimony whereof we hereunto affix our signatures, this 13 day of December, 1917.

OSCAR M. DAMM.
HERMAN WOBBE, JR.
